UNITED STATES PATENT OFFICE.

ANDREW G. OLSON AND JOHN A. DOLS, OF ELBOW LAKE, MINNESOTA.

GRAIN-CAR DOOR.

1,074,193.

Specification of Letters Patent. Patented Sept. 30, 1913.

Application filed January 29, 1913. Serial No. 745,040.

To all whom it may concern:

Be it known that we, ANDREW G. OLSON and JOHN A. DOLS, citizens of the United States, residing at Elbow Lake, in the county of Grant and State of Minnesota, have invented certain new and useful Improvements in Grain-Car Doors, of which the following is a specification, reference being had to the accompanying drawings.

10 This invention relates to improvements in grain car doors and more particularly to that class of doors which are sectioned.

An object of this invention is the provision of a sectional car door, in which tight 15 joints are provided between the respective sections, and between the door and the door posts, so that leakage of the grain from the car is prevented.

Another object of this invention is the 20 provision of a sectional car door, in which no nails or other similar fastening devices are passed through the sections and the door posts, so that the provision of new doors and posts will not be required as often as 25 heretofore.

A still further object of this invention is the provision of a sectional door for grain cars, in which the lower section of the door is provided with outlet openings so that the 30 pressure of the grain against the inner face of the door may be diminished, and the door may be readily removed from the door opening.

With these and other objects in view, our 35 invention consists in certain novel constructions, combinations and arrangements of parts to be hereinafter more fully described, claimed and illustrated in the accompanying drawings, in which—

40 Figure 1 is an inside elevation of a portion of a car showing the door applied. Fig. 2 is an outside elevation of a portion of a car showing the door applied. Fig. 3 is an inside elevation of a portion of the car 45 showing the door removed. Fig. 4 is a section on the line 4—4 of Fig. 1. Fig. 5 is a section on the line 5—5 of Fig. 1. Fig. 6 is a fragmentary section showing the cap removed from one of the outlet openings.

50 Referring more particularly to the drawings, the numeral 1 designates a portion of a grain car having the usual door openings 2 and door posts 3 at the opposite sides of the opening. Secured to the door posts are 55 metallic angle bars 4, the bars being adapted to cover the inner faces and the opposed

faces of the door posts to protect them from wear and to reinforce and strengthen the posts. The portion of the bars which engage the inner faces of the posts are provided with horizontal open ended slots 5, and the posts adjacent the slots 5 are undercut or grooved horizontally, as at 6, to provide recesses between the posts and the bars.

The doors, constructed in accordance with our invention, comprise a plurality of sections, it being understood that any number of sections desired may be used. In the accompanying drawings, we have illustrated upper sections 7 and lower sections 8, the sections 70 being provided with longitudinal flanges 9 which are adapted to overlap and provide tight joints between the sections of the door to prevent leakage of grain from the car.

The opposite ends of the sections are provided with open ended horizontal slots 10, the slots being spaced substantially the same distance, as the slots in the bars 4, so that the slots 5 in the bars and the slots 10 in the sections of the door will be disposed in alignment with each other. Secured to the opposite ends of the sections, are plates 11, the inner vertical edges of which are bent outwardly as at 12 to form hand holds, whereby the doors may be readily moved from place 75 to place. The outer vertical edges of the plates 11 adjacent their opposite side edges are formed with extensions 13, and formed in the extensions and the plates are horizontal slots 14, the slots in the plates and in the sections of the door registering.

The slots 14 in the plates are adapted to extend beyond the opposite edges of the door, so that the outer ends of the bolts 15 may engage in the outer ends of the slots 14 and the bolts 90 moved inwardly of the slots so that the heads 16 thereof may engage in the recesses formed by the grooves 6 between the door posts and the plates 4. The bolts 15 are provided with angular portions 17 adjacent the heads 16 thereof, the angular portions 17 being adapted to engage the slots 5 formed in the bars 4, to prevent turning of the bolts 15 relatively to the bars. When the bolts 15 are moved to their inward positions in the 95

registering slots in the sections of the door and bars 4, handled nuts 18 or burs 18' are threaded on the bolts against the outer face of the sections of the door to securely hold the door in position against the posts.

The plates 11 are preferably formed with arcuate ribs 19 which may be raised or

otherwise formed in the plates, the ribs being of a diameter slightly larger than the nuts, so that the nuts may bear against the plates within the ribs, and side sliding of the bolts will be prevented, thereby preventing accidental displacement of the doors.

If desired, cotter pins 20 may be passed through the bolts after the nuts 18 have been threaded thereupon to prevent accidental removal of the nuts from the bolts, thereby rendering the bolts non-removably mounted in the slots 10, being confined within the said slots by the edge portions of said plates 11, while being adapted to move sufficiently far therein to disengage the heads of the bolts from the slots of the bars 4.

The lower section 8 of the doors are formed with outlet openings 21 and secured to the inner face of the lower section adjacent the openings, are reinforcing and wearing plates 22, the plates being formed with threaded flanges 23 which project within the openings in the door, and threadably connected to the flanges 23 are caps or covers 24 for closing the openings. Chains 25 are secured at one end of the lower section 8 of the door adjacent the openings therein, the opposite ends of the chains being suitably connected to the caps 24 to prevent loss of the caps when they are removed from the flanges 23.

In the practical use of our car door, the several sections of the door are arranged within the car so that the slots 10 therein register with the slots 5 in the bars, whereupon the bolts 15 are engaged in the slots so that the heads 16 of the bolts are disposed in the recesses between the bars and the posts, whereupon the nuts 18 are mounted upon the bolts to bear against the plates 11, and the doors are maintained in position. It will be seen that the sections of one of the doors do not entirely close the opening at the upper end thereof and the car may be filled with grain or other material through this opening. When it is desired to remove the grain or other material from the car, the caps 24 are removed from the threaded flanges 23 in the outlet openings, so that a portion of the grain in the car may pass therefrom by gravity, and the pressure relieved from the door so that the sections thereof may be readily removed by unscrewing the nuts sufficiently to allow the bolts to be moved in the slots so that the heads may be disengaged from the bars 4.

It will be seen that with a door constructed in accordance with our invention, the sections thereof may be readily fastened to the door posts without the use of nails which pass through the posts and the door, and that the door may be repeatedly used without damage to either the door posts or the sections of the door.

It will be understood that we do not limit ourselves to the use of angle bars but that we may use ordinary slotted plates to form recesses to receive the heads of the bolts, and that the grain door can be constructed of either wood or metal, or both.

Having thus fully described our invention, what we desire to claim and secure by Letters Patent is:—

1. In combination with a vehicle having a door opening and door posts, slotted bars secured to said door posts, a door adapted to close said opening, said door having slots formed therein adapted to register with the slots in said bars, plates secured to said door and having slots therein, the slots in said plates and in said door registering with the slots in said bars, bolts arranged in said slots, nuts engaged upon said bolts and bearing upon said plates, and arcuate ribs formed on said plates and surrounding said nuts, as and for the purpose described.

2. In combination with a car having a door opening, vertical bars secured at the sides of the door opening and having horizontal slots intersecting their outer edges, a door adapted to close said opening, said door having horizontal slots adjacent to its opposite vertical edges and normally in registry with the slots in said vertical bars, said slots of the door being closed by the edge portions of said door, and bolts projecting through said slots and adapted to be moved sufficiently longitudinally of the slots to disengage the bolts from the slots of the bars, the movement of the bolts being limited by said edge portions of the doors, so that the bolts are always confined within the slots of said door.

In testimony whereof we hereunto affix our signatures in the presence of two witnesses.

ANDREW G. OLSON.
JOHN A. DOLS.
